Henry J. Miller

United States Patent Office.

HENRY J. MILLER, OF NASHUA, NEW HAMPSHIRE.

Letters Patent No. 69,112, dated September 24, 1867; antedated September 5, 1867.

IMPROVED BOOT-JACK AND BLACKING-BRUSH.

The Schedule referred to in these Letters Patent and making part of the same.

TO ALL WHOM IT MAY CONCERN:

Be it known that I, HENRY J. MILLER, of Nashua, in the county of Hillsborough, and State of New Hampshire, have invented certain new and useful improvements in the combination of a Boot-Jack and Blacking-Brush, of which the following is a full, clear, and exact description, reference being had to the accompanying drawings making part of this specification, in which—

Figure 1 is a bottom side view of my invention when opened to form a boot-jack.

Figure 2 a back side view when closed or shut together to form a blacking and a polishing-brush for blacking and polishing boots and shoes.

Figure 3 is a side elevation of fig. 2.

Figure 4 is an end elevation of fig. 1.

My invention consists in combining a boot-jack and a blacking-brush in a simple, cheap, and efficient manner, so that it may be very conveniently used for a boot-jack, a blacking-brush, or a polishing-brush by simply opening or closing it, as shown in the drawings, in which A A represent two arms formed in one, with the flanges B, the handles C, and sides D, which are cast in two parts and hinged together at the extremities of the handles, the hinging portions *k* being cast with the handles or fastened thereto. The longitudinal opening joint forms a division centrally between the two halves of the boot-jack hinged together as above stated, and between the two halves of the polishing-brush and the blacking-brush, as clearly shown in figs. 1, 2, and 4. The wood E, which holds the bristles of the polishing-brush, is secured to the sides D of the boot-jack by screws *h* passing through ears *g* and corner portions *f* into the wood. The wood F, of the blacking-brush, is fastened to the extremities of the arms A; through semicircular flanges *e* cast thereon. The flanges B project from the under side of the boot-jack, terminating in rounded ends *d*, which serve for feet to the boot-jack.

To use my improved device for a boot-jack it is opened or the two parts turned back, as shown in fig. 1, but the other side up, one foot placed on the top, the heel portion of the other boot placed between the two arms A, and the boot drawn off from the foot, as with the ordinary boot-jack. To use my improved device as a blacking-brush or a polishing-brush, the two parts are brought together, as shown in figs. 2 and 3, and it is ready for use. It will be observed that an ordinary blacking-box may be placed in the opening between the handles and the polishing-brush, as shown in red lines in figs. 2 and 3, which puts the whole apparatus into a convenient form for transportation, or it may be placed in a small box where it may be kept ready for use.

Having fully described my invention, what I claim as new, and desire to secure by Letters Patent, is—

The metallic frames, composed of the arms A A, sides D D, flanges B B, and handles C C, constructed and hinged together as herein represented, when used in combination with the brushes F and F, as and for the purpose specified.

HENRY J. MILLER.
